(57) **CLAIM**

We claim the ornamental design for a display screen with animated graphical user interface for vehicle status, as shown and described.

DESCRIPTION

FIG. 1 is a front view of a first image in a sequence for a display screen with animated graphical user interface for vehicle status;

FIG. 2 is a second view thereof;

FIG. 3 is a third view thereof; and,

FIG. 4 is a fourth view thereof.

The appearance of the animated sequence illustrated depicts transition between the images shown in FIGS. 1-4, but the process or period in which one image transitions to another forms no part of the claimed design. The outer broken line rectangle showing the display screen, and all other broken lines showing portions of the graphical user interface, form no part of the claimed design.
